(57) **CLAIM**

The ornamental design for a workspace partition, as shown and described.

DESCRIPTION

FIG. 1 is a perspective view of a workspace partition, showing my new design;

FIG. 2 is a top view of the workspace partition;

FIG. 3 is left side view, where each side is a mirror image of the other; and,

FIG. 4 is a front view thereof.

The broken lines showing a table and users are for the purpose of illustrating environmental structure and form no part of the claimed design.
